HOLDER FOR ROLL OF TAPE

Frank McCormick, Nyack, N. Y., assignor to Federal Carton Corporation, North Bergen, N. J., a corporation of New York

Application April 8, 1950, Serial No. 154,808

4 Claims. (Cl. 206—65)

This invention relates to an improved holder for rolls of tape such as masking tape and other re-usable tapes.

Such tape is commonly wound in cylindrical form on a hollow card-board center core. The tape is frequently sensitive to pressure thereon and deteriorates from such pressure. This raises difficulties in the shipment and handling thereof.

In order to meet these difficulties, it is preferable to pack each roll of tape in its carton in such a manner that the longitudinal side wall of the roll is prevented from abutting the side walls of the carton. It is possible to design a special carton with flaps which cooperate with the core of the roll of tape and prevent it from touching the sidewalls of the carton. However, such a construction is not satisfactory when it is desired to pack a plurality of rolls of tape in one carton and furthermore the roll of tape is subject to undue handling when it is removed from the carton.

According to the invention, there is provided an individual holder insert for each roll of tape. The holder comprises a base member with a pair of integral flaps. When the base member is placed in abutment with one of the faces of the roll of tape, these flaps may be positioned within the center core in abutment with the inner wall thereof. The flaps are so constructed that the roll is permitted to turn, but sideways movement thereof is inhibited. As a result, by making the size of the base greater than the size of the end face of the roll, it is possible to prevent the longitudinal wall of the roll from touching the side wall of any carton in which the holder and roll might be placed. Furthermore, the roll may be unrolled without removing it from its holder.

Each roll of tape may be provided with a single holder, or the roll may have two holders, each abutting a respective face of the roll. The use of two holders may be advisable in the case of the larger and heavier rolls of tape.

After the rolls of tape have been mounted on the holder inserts, the rolls may be packed in individual cartons, or a plurality of rolls may be placed in one carton. When the roll is individually packed, it is possible to unroll it without removing it from the carton. In any event, a roll of tape may be removed from a carton without detaching it from its holder, and as a result undesirable handling of the roll itself is held to a minimum.

The construction of the separate holder of this invention is more economical than the construction of a special carton. The holder insert may be used with a conventional carton. Furthermore, it is frequently desirable to wax any surface which comes into contact with the face of the roll in order to facilitate unrolling of the roll. It is more economical to wax the holder blank than to wax a carton blank, since considerable portions of the carton cannot come into contact with the face of the roll, and waxing of those portions is wasteful.

Other objects and advantages of this invention will be apparent from the following description and the annexed drawings, in which preferred embodiments are disclosed.

In the drawings,

Fig. 1 is a plan view showing a roll of tape mounted on a holder insert;

Fig. 2 is a section on line 2—2 of Fig. 1;

Fig. 3 is a view similar to Fig. 2, although reduced in scale, showing a plurality of rolls of tape mounted on holders and stacked;

Fig. 4 is a vertical section showing a roll of tape

2

mounted on upper and lower holders and packed in a carton;

Fig. 5 is a section on line 5—5 of Fig. 4;

Fig. 6 is a view similar to Fig. 3, showing a plurality of rolls of tape mounted on holders and being packed in a carton, the holders having respective apertures therein for reception of a mandrel;

Fig. 7 is a fragmentary vertical section of the improved holder, showing a score line formed by means of male and female dies; and

Fig. 8 is a view similar to Fig. 7, showing a score line formed by means of a male die and a flat die.

Upon reference to the drawings in detail, and in particular to Figs. 1 and 2, it will be seen that the improved holder comprises a base 10 with a pair of integral flaps 11 which are adapted to be interfit with a roll of tape 12.

This tape roll 12 is conventional and comprises tape of any suitable type, which is wound in layers around center core 14. This core 14 is generally made of card-board or other suitable material and is cylindrical in shape with open ends. Tape roll 12 is also cylindrical in shape with substantially parallel and planar end faces.

The invention is particularly useful when tape roll 12 is a masking tape or other type of tape which is sensitive to pressure thereon. This is because the holder tends to prevent the longitudinal side wall of roll 12 from coming into contact with the wall of any container in which said roll 12 might be placed.

The holder is preferably punched from a single blank, with flaps 11 integral with base member 10. This blank may be made of a suitable material which is relatively inexpensive, and which is stiff but permits sufficient articulation of flaps 11. Such a material may be one of a number of types of paper board, including kraft board, fibre board, corrugated board and cardboard. Board made with vulcanized fibre may also be used.

When the blank is made of solid kraft, a thickness of 0.028 inch has been found sufficient for commercial types of tape of a roll thickness up to 2 inches. Above that thickness, it is preferred to use board of about 0.042 inch thickness.

The above materials have been listed for illustrative purposes only, and the invention is not limited to those materials, nor to the illustrative thicknesses of the blank as listed above.

The blank may be unfinished, but it is preferably coated or impregnated with wax or other suitable material to prevent roll 12 from sticking to base 10 by reason of the exuding from between the layers of the tape of the rubber adhesive compositions used in making pressure sensitive tapes. Any suitable material may be used to make this exuded adhesive material non-adherent to the surface of base 10. Each surface of base 10 should be so treated if it is to be placed in abutment with an end face of a tape roll 12.

One important advantage of this treatment of the blank with wax is that it permits free turnability of roll 12 with respect to base 10.

Base 10 may be of any desired size and shape, so long as roll 12 nowhere protrudes over the edge of said base 10 when mounted thereon. Base 10 may be square with rounded corners, as clearly shown in Fig. 1, or round as clearly shown in Fig. 5. However, the invention is not limited to these shapes of base 10.

Flaps 11 oppose each other and are respectively cut out from base 10 and connected thereto by means of respective hinge lines 13. These hinge lines 13 are so formed that flaps 11 tend to return to the plane of base 10 when their detached peripheral edges 17 are held away from said plane. Hinge lines 13 are preferably parallel and equidistant from the center of base 10. The edges 17 are respectively convex and shaped in the form of an arc of a circle. Respective apertures 15 are formed in base 10 by reason of the cutting out of respective flaps 11.

In order to assemble the holder with tape roll 12, flaps 11 are pushed outwardly from base 10 and inserted through core 14. One face of roll 12 is brought to rest against base 10, in which position the ends of respective hinge lines 13 respectively approximately abut the inner

wall of core 14. When flaps 11 are released, they spring downwardly to approximately abut this inner wall of core 14 along substantially their entire respective detached peripheral edges 17.

The shape and positioning of flaps 11 in relation to base 10 and roll 12 may be further apparent when taken in conjunction with Fig. 2. It is to be noted that line 2-2 in Fig. 1 passes through point P, which is the center of base 10 and through which the axis of roll 12 passes when it is assembled with the holder. Also, line 2-2 passes through points M, which are the respective mid-points of respective lines 13, and through respective points L on the lower edges of the inner wall of core 14. The section on line 2-2 passes through points N on respective flap edges 17. The respective ends of each hinge line 13 meet the inner wall of core 14 at the respective points K, as shown in Fig. 1.

As is shown in the drawings, the center of the circle conforming to the shape of a respective edge 17 is located on a respective line passing through points M and N and at a point between the hinge lines 13.

The dimensions of flaps 11 and the distance between score lines 13 are what determine the effectiveness of the holder in preventing lateral movement of roll 12 while permitting said roll 12 to turn about its axis. The values of these dimensions of flap 11, as well as the distance between score lines 13, depend upon the dimensions of roll 12, and in particular the dimensions of core 14; practical considerations as to the structural strength of the holder and certain limitations which can be expressed mathematically.

The mathematical limitations can be readily determined with the aid of the following symbols:

d is the diameter of core 14;

m is the distance between score lines 13;

n is the length of each score line 13;

p is the distance MN between each line 13 and the outermost point of its respective associated edge 17; and

h is the distance NL between base 10 and the most distant point on a respective edge 17.

By the Pythagorean theorem, for each flap 11

$$MN^2 = ML^2 + LN^2$$

In symbols, this equation becomes

$$(1) \quad p^2 = \left(\frac{d-m}{2}\right)^2 + h^2$$

Also by the Pythagorean theorem, for each flap 11

$$PK^2 = PM^2 + MK^2$$

In symbols, this equation becomes

$$(2) \quad \left(\frac{d}{2}\right)^2 = \left(\frac{m}{2}\right)^2 + \left(\frac{n}{2}\right)^2$$

This equation reduces to

$$(2) \quad n^2 = d^2 - m^2$$

These Equations 1 and 2 are important in the light of the design consideration that the shape of each edge 17 should closely approximate the shape of the arc KNK of the ellipse which is the intersection of the inner wall of core 14 and the plane defined by point N on said edge 17 and its associated hinge line 13. When this condition is met, flaps 11 give maximum resistance to lateral movement of tape roll 12. However, edge 17 need not exactly conform to the shape of said ellipse arc KNK since edge 17 has a certain thickness and flexibility and will therefore approximately conform to the wall of core 14.

It is to be noted that for any value of m (the distance between lines 13), the ellipse of which said arc KNK is a portion will continuously decrease in width from its width at line 13 to zero width at point N. This condition should be met by edge 17. However, if MN is less than MK , and the center of the circle of which edge 17 is an arc lies within flap 11, this condition will not be met. Therefore, m should be restricted to values for which MN is less than or equal to MK , or in other words p is less than or equal to

Upon a comparison of Equations 1 and 2, it may be seen that for the condition

$$p \leq \frac{n}{2}$$

they yield

$$\left(\frac{d-m}{2}\right)^2 + h^2 \leq \frac{d^2 - m^2}{4}$$

This equation reduces to

$$m^2 - dm + 2h^2 \leq 0$$

By the quadratic formula, this equation gives the solution

$$(3) \quad \frac{1}{2}(d - \sqrt{d^2 - 8h^2}) \leq m \leq \frac{1}{2}(d + \sqrt{d^2 - 8h^2})$$

For Equation 3 to have real solutions, it is necessary that

$$d^2 - 8h^2 \geq 0$$

This reduces to

$$(4) \quad h \leq \frac{\sqrt{2}d}{4}$$

It is possible to select the size, shape and spacing of flaps 11 by means of Equations 1-4, for any value of the diameter d of core 14. In commercial practice, the diameter of the core of a pressure-sensitive roll of tape with which the improved holder is adapted to be used is frequently 3 inches. Therefore, the design factors for $d=3$ inches will be worked out in some detail, and it is understood that similar calculations can be made for other core diameters.

When $d=3$ inches is substituted in Equation 4, it is seen that h cannot exceed 1.06 inches. For the 3 inch core diameter, 1 inch therefore represents approximately the maximum amount that flap 11 can extend above base 10 and still have edge 17 substantially conform to the wall of core 14.

For $d=3$ inches, and for a selected value of h , it is possible to determine by means of Equation 3 the permissible range of values of m . Results for various values of h are tabulated as follows:

45	Selected Value of h (Inches)	Range of m (Inches)
50	1.06	0.01-2.99
	1.04	0.04-2.96
	1.02	0.10-2.91
	1.00	0.18-2.83
	0.98	0.29-2.72
	0.96	0.44-2.56
	0.94	0.65-2.35
	1.00	1.00-2.00
	1.06	1.50

On the basis of the above table, the preferred value of m , the distance between score lines 13, has been selected as approximately 1 inch. This ensures sufficient structural strength of the holder and at the same time permits the angle between a respective flap 11 and base 10 to be kept relatively small. However, the invention is not limited to this value of m .

Since the value of m is preferably well within the permitted range, to ensure satisfactory fit between flap edges 17 and the wall of core 14, the maximum value of h is preferably no more than approximately $3/4$ - $7/8$ inch.

In commercial practice, the cores of pressure-sensitive rolls of tape with which the holder is adapted to be used generally have varying thicknesses or heights in the range between $1/4$ and 4 inches, although the holder is not limited to use with cores having thicknesses within that range. The value of m having been fixed, the value of h is selected in accordance with the thickness of core 14. However, h preferably does not exceed approximately $3/4$ - $7/8$ inch.

The ratio of h to the thickness of core 14 depends upon a number of factors. Broadly speaking, h should be sufficiently large in relation to the thickness of core 14 so that there is adequate contact of the flap edges 17 with the wall of core 14, so as properly to limit lateral movement of roll 12. Also, the angle between respective flaps 11 and base 10 should be sufficiently small so that flaps 11 properly bear against core 14 at such an angle so as to limit lateral movement thereof, and so that there is proper spring tension tending to pull flaps 11 toward base 10.

In practice, the ratio between h and the height or thickness of core 14 depends upon a compromise between the above broad considerations. The factors determining the ratio include, but are not necessarily limited to, the dimensions of core 14, the weight of roll 12, the distance m between score lines 13, the manner in which score lines 13 are formed, the material of which the holder is made, and whether or not holders are applied to both faces of roll 12.

Once the value of h has been selected, as a result of consideration of the above factors, it is possible to determine the dimensions of flaps 11 by means of Equations 1 and 2.

For example, Figs. 1 and 2 have been drawn to exact scale for the construction in which the diameter d of core 14 is 3 inches, and its height is $\frac{3}{4}$ inch. The distance $\overline{LN}$, or h , has been selected as $\frac{3}{8}$ inch, or half the height of core 14; but it is to be understood that this value of h is illustrative only, since h must be determined on the basis of the factors listed above. The distance m between score lines 13 is one inch. As a result, from Equation 1 it is seen that the distance $\overline{MN}$, or p , is 1.07 inches; and the length n of each score line 13 is 2.83 inches. The shape of edge 17 is that of the arc $\overline{KNK}$ of a circle extending through point N and at the ends of score line 13.

The dimensions of the holder shown in Figs. 1 and 2 agree substantially with those calculated, making allowance for deviations caused by the thickness of score lines and of cut lines. Each edge 17 approximately conforms in shape along substantially its entire length to the shape of the inner wall of core 14. Any slight divergencies in fit are compensated for by the thickness and limited deformability of flap edge 17.

Similarly as in the above example, the dimensions of flaps 11 can be suitably chosen for any diameter and height of core 14. Flaps 11 will resist lateral movement of roll 12 with respect to base 10, but since edges 17 conform to the wall of core 14, said roll 12 is freely turnable on the holder. As a result, roll 12 may be used with minimum direct handling thereof.

It has been found good practice for certain tape rolls to apply holders to each face thereof. This is shown in Figs. 4 and 5, in which identical holders, as described above, are shown respectively applied to the upper and lower end faces of tape roll 12. Such an arrangement is particularly useful in the case of heavier rolls of tape, such as commercial rolls having a height of 2 inches and greater. In that case, since the value of h is limited to approximately $\frac{3}{4}$ – $\frac{7}{8}$ inch, the ratio of h to the height of core 14 is unfavorable when only a single holder is used. The use of two holders adds structural strength.

The tape roll 12, together with either one or two holders mounted on its respective end faces, may be packed in individual cartons. This is shown in Figs. 4 and 5, in which roll 12 is packed in carton 20. Base 10 and flaps 11 hold roll 12 spaced from the side walls of said carton 20.

When this method of packing is used, roll 12 may optionally be unrolled without its being removed from carton 20. Figs. 4 and 5 show closure flap 21 in its open position and the end 12a of roll 12 extending outside carton 20. Since flap edges 17 substantially conform to the shape of the wall of core 14, said wall of core 14 can turn with respect to flaps 11. Vertical movement of roll 12 is limited by the upper and lower walls of carton 20.

Optionally, as shown in Figs. 4 and 5, base 10 may be round, and this is advantageous if for some reason roll 12 does not turn freely with respect to flaps 11. In that case, base 10 also turns, and roll 12 unrolls freely. Base 10 may also be of suitable polygonal or other shape so that it turns freely in carton 20.

Besides being packed individually, a plurality of tape rolls 12, each mounted either on a single holder or on two holders, may be packed in a single carton. This is clearly shown in Figs. 3 and 6.

Fig. 3 shows a plurality of holders, each having a tape roll 12 mounted thereon, packed in carton 16. The outline of this carton 16 is shown in broken lines since it may be of any conventional type. Preferably, the side walls of carton 16 abut the side edges of base 10 to prevent lateral movement thereof. Also, the top wall of carton 16 abuts the top of the uppermost roll 12, or optionally suitable spacers are placed in the top of said carton 16.

Fig. 6 shows a carton 16a whose top flap 17 is in its open position. Two rolls 12 have been packed in this carton 16a by means of mandrel 18, and a third roll 12 is in the process of being packed.

5 This mandrel 18 and the parts associated therewith are not shown in detail. Mandrel 18 is preferably cylindrical and is initially placed in carton 16a with its lower end extending through aperture 19 in the base of said carton 16a. In this modification, aperture 24 is provided in the center of each base 10, whereby the holders may be dropped over mandrel 18 into carton 16a. After carton 16a has been packed, mandrel 18 may be removed.

Figs. 7 and 8 show alternate types of score lines 13. In Fig. 7, said score line 13 is formed by applying respective female and male dies to the respective upper and lower faces of base 10. As a result, a ridge 23 is formed in the upper face of base 10, and a parallel groove 22 is formed directly beneath this ridge 23 in the lower face of base 10. Groove 22 and ridge 23 together define score or hinge line 13. This results in a spring-like action tending to return flap 11 to the plane of base 10 when this flap 11 is lifted to the position of Fig. 7. As a result, flaps 11 grip the wall of core 14 and are not readily lifted upward by lateral force on roll 12.

The construction of Fig. 8 may optionally be employed when a more intensified spring-like action on flaps 11 is desired. In this construction, a flat die, instead of a female die, is applied to the upper surface of base 10, and as a result ridge 23 is eliminated.

Preferred embodiments of the invention, as well as various changes, omissions, substitutions and variations which can be made therein, have been disclosed. Numerous other changes, omissions, substitutions and variations can be made without departing from the scope and spirit of the invention.

Edge 17 need not be an arc of a circle and optionally may have any suitable shape approximately corresponding to the shape of the arc $\overline{KNK}$ of the ellipse which is the intersection with the inner wall of core 14 of the plane defined by line 13 and point N.

The improved holder may be used with rolls of tape, including pressure-sensitive tape, and with other types of rolls, such as rolls of ribbon. Any roll can be used, so long as it has an end wall and an opening communicating with that end wall, said opening having a cylindrical side wall.

What is claimed is:

1. In combination with a roll which has a cylindrical bore which has a rigid side wall, and an end wall which is transverse to the axis of said bore, said bore extending through said end wall, a holder comprising a planar base which abuts said end wall, and a pair of opposing cut-out planar flaps which are connected to said base by means of parallel scored hinge lines of the same length, said flaps being inclined outwardly from said respective hinge lines at an acute angle with respect to said base and being positioned within said bore, the respective ends of said hinge lines being proximate to said side wall, said hinge lines being so formed as to exert a force on said flaps tending to return them to the plane of said base and thereby maintaining their detached peripheral edges in abutment with said side wall, the detached peripheral edge of each said flap being in the shape of a minor arc of a circle having the hinge line of said flap for a chord, the maximum distance from said hinge line to said detached peripheral edge exceeding the distance between said hinge line and said side wall and being less than or, at most, equal to one half the length of said hinge line, each said detached peripheral edge approximately corresponding to the curve of intersection of the plane of said flap with the inner face of said side wall, whereby said flaps resist lateral movement of said roll with respect to said base but permit said roll to turn about the axis of said opening with respect to said base.

2. A combination in accordance with claim 1, in which the entire peripheral edge of said base extends beyond the longitudinal outer surface of said roll.

3. In combination with a roll which has a cylindrical bore which has a rigid side wall, and an end wall which is transverse to the axis of said bore, said bore extending through said end wall, a holder comprising a planar base which abuts said end wall, and a pair of opposing cut-out planar flaps which are connected to said base by means of parallel scored hinge lines of the same length,

said flaps being inclined outwardly from said respective hinge lines at an acute angle with respect to said base and being positioned within said bore, the respective ends of said hinge lines being proximate to said side wall, said hinge lines being so formed as to exert a force on said flaps tending to return them to the plane of said base and thereby maintaining their detached peripheral edges in abutment with said side wall, the detached peripheral edge of each said flap being convex and being symmetrical with respect to the perpendicular bisecting line within said flap of said hinge line, the maximum distance from said hinge line to said detached peripheral edge exceeding the distance between said hinge line and said side wall and being less than or, at most, equal to one half the length of said hinge line, each said detached peripheral edge approximately corresponding to the curve of intersection of the plane of said flap with the inner face of said side wall, whereby said flaps resist lateral movement of said roll with respect to said base but permit

said roll to turn about the axis of said opening with respect to said base.

4. A combination in accordance with claim 3, in which the entire peripheral edge of said base extends beyond the longitudinal outer surface of said roll.
